(57) **CLAIM**

I claim the ornamental design for a meter, as shown and described.

DESCRIPTION

FIG. 1 is a front view of a portion of a meter, such as a multimeter.

FIG. 2 is a front view of another portion of a meter, such as a multimeter.

FIG. 3 is a front view of yet another portion of a meter, such as a multimeter.

FIG. 4 is a front view of a meter, such as a multimeter.

FIG. 5 is a rear view of the meter of FIG. 4.

FIG. 6 is a left-side view of the meter of FIG. 4.

FIG. 7 is a right-side view of the meter of FIG. 4.

FIG. 8 is a top view of the meter of FIG. 4; and,

FIG. 9 is a bottom view of the meter of FIG. 4.

Portions of the meter shown in broken lines are included for the purpose of illustrating environment and form no part of the claimed design.

1 Claim, 7 Drawing Sheets
